US00D968592S

(12) United States Design Patent (10) Patent No.: US D968,592 S
(45) Date of Patent: * Nov. 1, 2022

(54) ORAL CLEANING TOOL

(71) Applicant: Jufen Wei, Guilin (CN)

(72) Inventor: Jufen Wei, Guilin (CN)

() Term: 15 Years

(21) Appl. No.: 29/805,063

(22) Filed: Aug. 24, 2021

(51) LOC (13) Cl. 24-02

(52) U.S. Cl.

USPC D24/119

(58) Field of Classification Search

CLAIM

The ornamental design for a oral cleaning tool, as shown and described.

DESCRIPTION

FIG. 1 is a perspective view of a oral cleaning tool showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.
